UNITED STATES PATENT OFFICE.

THOMAS SIMMONS HOMANS, OF BROOKLYN, NEW YORK, ASSIGNOR
TO MERGENTHALER LINOTYPE COMPANY, A CORPORATION OF
NEW YORK.

LINOTYPE-MACHINE.

No. 830,436.

Specification of Letters Patent.

Patented Sept. 4, 1906.

Application filed March 23, 1906. Serial No. 307,759.

To all whom it may concern:

Be it known that I, THOMAS SIMMONS HOMANS, of the borough of Brooklyn, county of Kings, and State of New York, have invented 5 a new and useful Improvement in Linotype-Machines, of which the following is a specification.

This invention has reference to that class 10 of linotype-machines wherein circulating matrices are stored in two magazines, from which they are delivered to a single composing mechanism in order that the line may be composed at will of matrices from either or both magazines, as represented in Letters Patent 15 of the United States Nos. 640,033, 795,878, 798,298, and 799,943 and now known commercially as the "Mergenthaler Double-Magazine Linotype-Machine."

The object of the invention is to facilitate 20 the independent removal and the application of the magazines, so that magazines carrying matrices of any desired faces or fonts may be speedily brought into use. To this end the upper magazine is constructed and arranged 25 for removal in a downward and forward direction and combined with mechanism for lifting it from its operating position and giving it support during its application and removal. The lower magazine is mounted on 30 a movable support adapted to be instantly moved rearward in such manner as to support the magazine in position to admit of its being readily withdrawn.

The escapement devices for releasing the 35 matrices from the magazines may be attached to and made permanent parts of the magazines, as usual; but I prefer to employ stationary escapement mechanisms sustained in the main frame and adapted to permit the 40 independent removal of the magazines, so that the escapement mechanisms remaining in the machine may be employed in connection with any and all magazines applied thereto.

With the exception of the parts shown and hereinafter specifically described the machine may be of any ordinary or appropriate 45 construction, the drawings being restricted to those parts with which my improvements 50 are directly associated.

Referring to the drawings, Figure 1 is a side elevation of the upper part of a machine having my improvements embodied therein

with the parts in operative position, the upper ends of the magazines and the distributor 55 mechanism being shown in vertical section. Fig. 2 is a similar view with the parts adjusted preparatory to the removal of the magazines. Fig. 3 is a vertical section from front to rear through the lower ends of the magazines, the escapement mechanism, and adjacent parts, the magazines being separated from the escapements preparatory to removal. Fig. 4 is a cross-section on the line 44, Fig. 1, illustrating more particularly the 60 mechanism for raising and lowering the forward ends of the magazines. Fig. 5 is a section on the line 55, Fig. 1, illustrating more particularly the pivotal supports for the upper ends of the magazines. Fig. 6 is a perspective view of the supporting-frame for the upper magazine detached from the main frame. Fig. 7 is a perspective view of the supporting-frame for the lower magazine detached from the main frame. 75

Referring to the drawings, A represents a rigid main frame; B, the upper inclined magazine adapted to contain a font or set of matrices Y; B', a second underlying magazine also adapted to contain a set or font of matrices; G, a vertically-channeled front plate to which the matrices are delivered from the upper magazines as they are released one at a time; H, an inclined assembler-belt by which the matrices from the upper magazine are 85 delivered to the assembling mechanism; b, a belt to which the matrices are delivered from the lower magazine B' and by which they are delivered through intermediate guides to the assembling mechanism. 90

The foregoing parts are of the same general character and have the same functions as the parts represented by like letters in Patent No. 640,033, each magazine being provided with an escapement mechanism connected 95 with finger-keys, so that as the keys are manipulated letters bearing corresponding characters are delivered from one magazine to another and conducted to the line in composition, as heretofore. My present invention 100 relates to the mode of constructing and supporting the magazines and to the improved details of the escapement mechanism as follows: Each magazine consists, as usual, of two parallel plates secured to, intermediate 105 spacing-pieces and provided in their inner

opposing faces with longitudinal grooves or channels to receive and guide the edges of the matrices which enter the magazines from the distributing mechanism at the upper end and escape one at a time at the lower end and are controlled by the escapement devices. The upper magazine B is removably seated on an underlying base-frame b', which remains permanently in the main frame. The base-frame b' is sustained at its upper end upon and arranged to pivot on a horizontal rod b², fixed in the main frame, and this in order that the lower end of the frame b' and the magazine B thereon may be lifted above their normal or operative positions. The lower end of the base-frame b' carries a transverse rock-shaft b³, having at opposite ends two arms b⁴ and two eccentrics b⁵, the latter resting on studs or rollers b⁶ on the main frame. When the arms and eccentrics stand in the position shown in Fig. 1, the magazine and its base-frame are in operative position. When the magazine is to be removed, the arms b⁴ are turned forward, as indicated by the dotted line in Fig. 1, until they assume the forward position, (shown in Fig. 2,) this motion of the arms being accompanied by a rotation of the cams b⁵, which serve to lift the lower end of the frame b' and the magazine thereon above their normal positions and give them support in the new position, as shown in Fig. 2, so that the lower or forward end of the magazine stands above the channel-plate G and in position to be drawn forward from the machine without interference with the other parts.

The magazine is provided on its under side with a series of transverse bars or ribs to give it the required rigidity, one of these bars near the upper end being extended laterally on each side, as shown at b⁷, so that when the magazine is permitted to slide forward and downward from the machine the ends of the bar will ride upon and be sustained by the arms b⁴, so that the magazine may be permitted to assume a pendent position, as shown in dotted lines in Fig. 2. Being thus sustained, it may be conveniently grasped, removed from the machine, and transferred to a rack or other support.

In applying the magazine to the machine it may be suspended on the arms, as shown, and then tipped upward at the forward end and slid upward and backward to its operative position. It will be observed that the removal and replacement may be easily performed, first, because the magazine constructed without the usual heavy base-frame is comparatively light, and, second, because it is guided and a large portion of the weight sustained by the frame during its movement to and from the operative position. When the magazine is in place, one of the cross-bars at the lower end bears behind a shoulder on the base-frame, whereby it is prevented from

sliding upward. In order to effect its removal, it is only necessary to raise the lower end of the magazine by hand until the bar is disengaged.

Passing now to the lower magazine B', it is removably seated on top of a skeleton base-frame b⁸, having longitudinal side plates b⁹, containing slots b¹⁰ and supported by rigid studs b¹¹ on the main frame extending into the slots. The main frame is provided at the rear side beneath the base-frame b⁸ with rollers or supports b¹². The arrangement of parts is such that when the magazine is to be removed the base-frame may be drawn backward from its normal position (shown in Fig. 1) to the position shown in Fig. 2. It is supported and guided during this movement by the studs b¹¹ and rollers b¹², and at the conclusion of the backward movement it is firmly supported in the position shown in Fig. 2. It will be observed that this backward movement has the double effect of carrying the magazine rearward and outward from the frame and also of tipping its rear end downward, so that it stands in position to be conveniently grasped by the attendant standing behind the machine, who is thus enabled to draw the magazine rearward from the base-frame and remove it from the machine quickly and easily.

The lower magazine B' is essentially of the same construction as the upper magazine, being stiffened on its under side by transverse ribs or bars and being adapted to slide freely in an endwise direction upon and off from the base-frame. In order to facilitate the application of the magazine B', it is preferably adapted to interlock with the base-frame when nearly withdrawn, so that it may assume a pendent position, as indicated by dotted lines in Fig. 2. Any suitable formation of the parts to this end will answer; but it is preferred to construct the base-frame b⁸ with terminal hooks b¹³, adapted to engage one of the cross-bars projecting from the magazine.

It will be observed that to remove the lower magazine it is only necessary to draw the base-frame b⁸ rearward and thereafter draw the magazine rearward from the frame with or without permitting its suspension at the end. To apply the magazine, it is only necessary to slide it to its place on the base-frame b⁸ and thereafter push the frame forward to its place.

Referring now to the escapement mechanism for releasing the matrices from the respective magazines, attention is directed to Fig. 3, in which C represents the escapements of the upper magazine and C' the escapements of the lower magazine. Each of these escapements consists, as usual in linotype-machines, of a centrally-pivoted lever carrying at opposite ends two pawls or dogs, which are projected alternately into the magazine

in order to control the passing matrices, which are delivered one at a time from the open end of the magazine. There is, as usual, an escapement for each channel of each magazine.

5 The escapements of the upper magazine are arranged to act on its under side, while those of the lower magazine act from its upper side. Both series of escapements are mounted in transverse bars c^2 and c^3 , secured to and forming, in effect, a part of the main frame, so that the escapements may remain in position in the machine when the magazines, or either of them, are removed. Each escapement is acted upon by a spring c^4 , attached to its supporting-bar and tending to reverse the position of the escapement and project the upper pawl into the magazine. The escapements are controlled in their action by vertically-reciprocating bars or reeds D , each 15 urged constantly downward by a spring E and connected with a finger-key mechanism, such as shown in Letters Patent of the United States No. 530,931, or any equivalent mechanism for lifting the bars. The springs E are of sufficient strength to overcome the springs c^4 and hold the escapements normally in the position shown in Fig. 3. When the finger-key is actuated and the bars lifted, the position of the escapements is reversed and a single matrix is released. Each bar D connects directly with an escapement of the upper magazine, and also through an intermediate lever c^5 and link c^6 with the corresponding escapement of the lower magazine. In order to prevent the release of matrices from both magazines, two rock-shafts F and F' are extended across the machine in position to engage the respective series of escapements, these shafts being connected in such a manner as to turn in unison and so that when one series of escapements is locked against movement the other is unlocked. These escapement connections are essentially the same as in the present linotype-machines and are not claimed in themselves as a part of the present invention.

It will be observed that the magazines are constructed with transverse slots b^{15} in one side and that the escapement-supporting bars c^2 and c^3 are formed with ribs adapted to guide the escapement-pawls and to fill the slots b^{15} when the magazines are in operative position, so that the ribs form, in effect, a part of the grooved magazine-plate and aid in guiding the edges of the matrices.

It is obvious that when the stationary escapements are used in connection with removable magazines the latter must be moved sidewise away from the escapements before they can be withdrawn endwise from the machine. This separation of the upper magazine from its escapements is effected by the lifting movement of its base-frame b' , already described. In the case of the lower magazine B' the separation from the escape-

ments is effected by lowering the magazine, as shown in Fig. 3. To permit of this action, the lower end of its base-frame b^8 is supported when in operative position by eccentrics b^{16} , carried in opposite ends of a horizontal rock-shaft b^{17} , mounted in the main frame, and provided with an operating-handle b^{18} . After the base-frame is pushed forward to its operative position with the magazine thereon the handle is turned and the eccentrics caused to lift the frame b^8 and the magazine until the latter bears snugly against the under side of the escapement-bars c^2 . The bars are so proportioned that the eccentrics will stand "upon the center" or assume such position that they will hold the magazine rigidly in place. When the magazine is to be removed, the eccentrics are turned and the frame b^8 and the magazine lowered to the position shown in Fig. 3.

I believe the present to be the first machine in which two independently and longitudinally movable magazines have been combined with an intermediate dual escapement mechanism—that is to say, a mechanism comprising escapements to coöperate with both magazines—and it will be understood that the details of construction may be widely modified provided the general relation of the parts and the independent removability of the magazines in substantially the manner described is retained.

While I prefer to support the lower magazine on a sliding and tilting frame of the form shown, it is to be understood that I believe the present to be the first instance in which a magazine has been mounted on a frame or equivalent support permitting the magazine to be moved backward and downward and there supported in position to be conveniently removed from the machine, and it is manifest that the details of these parts may be widely changed without, in fact, changing the mode of operation. I also believe the present machine to be the first in which a stationary escapement mechanism has been combined with a detachable magazine and means for positively moving the magazine into operative relation with the escapements acting through its side, and it is manifest that the form of the supporting-frame b^8 and of the lifting devices b^{16} may be varied at will, provided they have essentially the mode of action herein described.

The composed lines of matrices will be disintegrated and the matrices delivered to the upper ends of the respective magazines by any suitable distributing mechanism. In the drawings I have shown a mechanism essentially such as that shown in the Letters Patent above referred to. The upper distributing-bar I and its adjuncts deliver the matrices through the channeled throat B^2 , hinged to the base-frame b' , into the upper magazine. The lower distributor-bar I' and

its adjuncts deliver the matrices into the lower magazine B' through the channeled throat B⁴, hinged to the base-frame b⁸. The lower distributor is carried, as usual, in pendant pivoted arms i, which may be swung upward and backward, as shown in Fig. 2.

While I have represented herein an approved form of escapement which I prefer to retain, it is to be understood that it may 10 be replaced by escapement devices of any other form which will act to control the passing matrices in the magazine and deliver them one at a time.

It is to be understood that while the escapement mechanism as a whole is fixed to the 15 main frame and designed to remain permanently in place it may be conveniently detached and removed for adjustment or repair.

When the magazines are removed away 20 from the escapements, it is necessary to prevent the escape of the matrices. This may be done by any suitable locking devices—such, for instance, as transverse bars K—thrust transversely through the magazines 25 in position to engage the ears of the matrices.

Having described my invention, what I claim is—

1. In a linotype-machine, the combination 30 of two parallel longitudinally-removable magazines, an intermediate fixed dual escapement mechanism acting through the sides of the respective magazines, and mechanism for moving the magazines independently to and from the respective escapement mechanisms.

35 2. In a linotype-machine, the combination of the two series of escapements fixed in position and acting one upward and the other downward, the magazine overlying the upper escapements, a second magazine underlying the lower escapements, means for moving the magazines independently to and from the escapements, and means for supporting the magazines during their longitudinal removal.

45 3. In a linotype-machine, two magazines one overlying the other, the upper magazine removable in a forward direction, and the lower magazine removable in a rearward direction, in combination with an intermediate 50 dual escapement mechanism and means for moving and supporting the magazines away from the escapements preparatory to their removal.

4. Upwardly and downwardly acting escapements and a common operating means 55 therefor fixed in the main frame, in combination with the overlying and underlying magazines, means for lifting and sustaining the upper magazine, and means for lowering and 60 sustaining the under magazine, whereby the independent removal of the magazines in opposite directions is permitted without disturbing the escapement mechanism.

5. In combination with a series of escapements C', an underlying magazine B' coöper-

ating therewith, a magazine-supporting frame b⁸, and mechanism for raising and lowering said frame.

6. In a linotype-machine, the combination 70 of a main frame, a secondary frame mounted in the main frame to sustain the magazine in its operative position and arranged to slide endwise from its normal position, and a magazine seated upon the secondary frame and movable endwise therewith and also removable therefrom; whereby the magazine may be carried bodily from its operative position and sustained during removal from the machine.

7. In a linotype-machine, the combination 80 of a main frame, an inclined removable magazine, and a secondary frame to sustain the magazine in its operative position, said secondary frame movable bodily in an endwise direction rearward and downward, with 85 the magazine thereon; whereby the removal and application of the magazine is facilitated.

8. In a linotype-machine, and in combination with the magazine B' removably mounted thereon, a sliding and tilting frame b⁸ 90 whereby the magazine may be moved from its operative position and supported in position to permit of its convenient removal.

9. In a linotype-machine, a main frame, and an escapement mechanism fixed therein, 95 in combination with a removable magazine coöperating with said escapement mechanism, and a magazine-support arranged to move longitudinally with the magazine thereon to facilitate the removal and insertion of the magazine, and means for moving said support laterally to establish operative relation of the magazine with the escapements and to separate the magazine therefrom preparatory to removal.

10. In a linotype-machine, a series of downwardly-acting escapements C', the underlying magazine B', the frame b⁸ mounted to slide and to turn on pivotal supports near the upper end, and lifting devices for said 110 frame near its lower end.

11. In a linotype-machine, and in combination with fixed escapements C', the detachable magazine B' with tilting and sliding frame b⁸, and eccentrics for raising and lowering 115 the same.

12. In a linotype-machine, a main frame, a longitudinally-removable magazine, and a magazine-supporting frame mounted to slide longitudinally upon, and rock about, a supporting-axis.

13. In combination with the fixed coöperating escapement mechanism, the swinging and sliding frame b⁸, lifting devices therefor, and a magazine B' mounted on said frame 125 and adapted to slide longitudinally therefrom.

14. In a linotype-machine, in combination with the main frame, a magazine-supporting frame mounted in the main frame and mov- 130

able bodily in a rearward direction from its operative position, and provided with means for suspending the magazine when withdrawn, and the magazine supported on the 5 movable frame and removable in an endwise direction therefrom.

15. In a linotype-machine, a main frame, a secondary frame mounted to move bodily endwise therein, a fixed escapement mechanism, and a magazine sustained by and movable with the secondary frame to and

from the escapement mechanism, said magazine being slidably and removably mounted on the secondary frame.

In testimony whereof I hereunto set my 15 hand, this 20th day of March, 1906, in the presence of two attesting witnesses.

THOMAS SIMMONS HOMANS.
